UNITED STATES PATENT OFFICE.

JAMES G. SCOTT, OF TULSA, OKLAHOMA.

SELF-WRINGING MOP.

1,126,887.

Specification of Letters Patent.

Patented Feb. 2, 1915.

Application filed October 14, 1913. Serial No. 795,110.

To all whom it may concern:

Be it known that I, JAMES G. SCOTT, a citizen of the United States, residing at Tulsa, in the county of Tulsa and State of Oklahoma, have invented a new and useful Self-Wringing Mop, of which the following is a specification.

The invention relates to improvements in mops.

10 The object of the present invention is to improve the construction of mops, and to provide a simple, practical and inexpensive mop of strong and durable construction, adapted to hold a mop cloth firmly in proper 15 position for use, and capable of exerting the desired pressure on the cloth and of permitting the latter to be easily and quickly changed when desired, the holding means for the cloth being such as to obviate the 20 necessity of employing endless bands or mop cloths.

A further object of the invention is to enable the wringing loop to be arranged directly at the front end of and substantially 25 in line with the handle, and to permit the mop cloth supporting means to swing out of the way of the loop when it is desired to wring the mop cloth.

Another object of the invention is to construct the mop cloth supporting means in 30 the form of a pan, adapted to be conveniently employed for dipping water from a bucket, or other receptacle, for wetting a floor or other surface to be scrubbed or 35 washed.

With these and other objects in view, the invention consists in the construction and novel combination of parts hereinafter fully described, illustrated in the accompanying 40 drawing, and pointed out in the claims hereinafter appended; it being understood that various changes in the form, proportion, size and minor details of construction, within the scope of the claims, may be resorted to 45 without departing from the spirit or sacrificing any of the advantages of the invention.

In the drawing: Figure 1 is a perspective view of a self wringing mop, constructed 50 in accordance with this invention. Fig. 2 is a longitudinal sectional view of the same. Fig. 3 is a plan view partly in section. Fig. 4 is a longitudinal sectional view of a portion of a mop having arched arms.

55 Like numerals of reference designate cor-

responding parts in all the figures of the drawing.

In the accompanying drawing in which is illustrated the preferred embodiment of the invention, 1 designates a handle provided in 60 the underside with a longitudinal groove 2 for the reception of a mop wringing rod 3 secured in the groove 2 of the handle by staples 4, or other suitable fastening means, and provided at its upper or rear end with 65 a crank 5 and having a knob or grip 6 at the outer end of the crank. The mop handle 1, which is preferably constructed of wood, is reinforced at the upper or rear end by a metallic ferrule 7 adapted to prevent 70 the handle from splitting. The rod 2 is provided at its front end with a loop 8 located at the lower or front end of the handle 1, and adapted to receive a mop cloth 9. The 75 mop cloth 9, which consists of a strip of material, is passed through the loop 8 and is doubled to form two thicknesses, as shown, and it is arranged beneath a plate 10 of substantially oblong form, constructed 80 of stout sheet metal and adapted to maintain the mop cloth in the spread condition and in proper position for use. The plate 10 is provided with side walls or flanges 11, and its outer or front end is bent upwardly to form 85 a front inclined wall or flange 12, which is rigidly connected with the adjacent portions of the side walls or flanges 11. The terminal portions of the sides of the folded mop cloth 9 are extended upwardly and inwardly over the front end wall or flange 12, and it is 90 held firmly against the same and against the adjacent portion of the plate 10 by a clamp 13, constructed of rod metal or other suitable material and consisting of a crank bend, 95 terminal pivots 14 and 15 and a handle 16, extending from one of the pivots. The pivots 14 and 15 are mounted in perforations of the side walls or flanges, and the crank bend, which extends entirely across the plate, is adapted to swing toward the 100 end flange or wall 12 in moving to its engaging position, and it co-operates with the said end wall in holding the ends of the mop cloth. By clamping the ends of the 105 mop cloth in this manner, it is unnecessary to sew the terminals of the cloth together, as is ordinarily done with mops of this character, and the mop cloth is adapted to be easily and quickly removed when desired.

The handle 16 of the clamp is arranged at 110

the outer face of one of the side walls or flanges and is adapted to be swung upwardly and downwardly to operate the clamp. The side walls or flanges 11 are pivoted at 5 a point intermediate of the ends of the plate to the outer terminals of spaced arm 17 by rivets 18, or other suitable fastening devices, and the said arms 17 are provided at their 10 inner ends with transverse connecting portions 19 having shanks or attaching portions 20 located at opposite sides of the lower end of the handle of the mop, and riveted or otherwise secured to the same. The spaced arms 17, which are rigid with the mop handle, are bent at an intermediate point, the 15 inner portions of the arms being arranged at an obtuse angle to the handle and extending outwardly at an angle to the loop 8 thereby spacing the outer portions of the 20 arms upwardly from the plane of the said loop 8 and providing a space on the under edges of the arms 17 to receive the inner portion of the pivot plate 10, which inner portion is adapted to swing upwardly 25 against the lower edges of the outer portions of the arms to arrange the plate out of the way of the loop 8 when it is desired to twist the mop for wringing or expelling the water therefrom. Instead of constructing 30 the arms 17 of angular form, they may be curved or arched as shown at 17^a in Fig. 4 of the drawing to provide the said space to arrange them and the pivot plate clear of the loop 8. This construction enables the 35 loop 8 to be arranged directly at the lower end of the handle where it is out of the way when the mop is in use, and when the plate is swung into alignment with the outer portions of the arms 17, the latter extend 40 between the side walls or flanges and brace the said plate and prevent the same from twisting during the wringing operation. In wringing the mop, the handle 1 is grasped with one hand and the crank 5 is turned 45 with the other hand. The pivotal connection between the plate and the arm 17 enables the plate to be arranged at different angles with relation to the arm to adjust it- self to a floor or other surface operated on

by the mop. The side walls or flanges 11 and the front end wall or flange 12, besides co-operating with the arm 17 and the clamp 13, are adapted to form a pan or receptacle to enable water to be dipped from a pail or other receptacle for wetting a floor or other 50 surface. The mop is adapted for scrubbing, polishing floors and for washing woodwork and dusting walls and the like, and a mop or polishing cloth for any particular purpose may be readily applied to the mop. 55

What is claimed is:—

1. A mop of the class described including a handle, a rod mounted on the handle and provided with a loop adapted to receive the inner portion of a mop cloth, arms rigidly connected with the handle, a plate provided with side walls pivoted to the said arms, said plate being also provided at the outer end with a transverse wall set at an inclination and connecting the side walls to enable the plate to operate as a dipper, and a clamp consisting of a rod mounted in the side walls or flanges and extending across the outer portion of the plate and having a crank bend arranged to co-operate with the 65 said inclined wall or flange in clamping the outer portion of the mop cloth. 70

2. A mop of the class described, including a handle, a rod mounted on the handle and provided with a loop adapted to receive the inner portion of a mop cloth, arms rigidly connected with the handle, a plate provided with side walls pivoted to the said arms, said plate being also provided at the outer end with a transverse wall or flange 80 connecting the side walls to enable the plate to operate as a dipper, and means carried by the outer portion of the plate for securing the outer portion of a mop cloth, whereby the plate is adapted to hold the mop cloth to its work. 85

In testimony that I claim the foregoing as my own, I have hereto affixed my signature in the presence of two witnesses.

JAMES G. SCOTT.
